UNITED STATES PATENT OFFICE.

AUGUST A. WALL, OF BROOKLYN, NEW YORK.

TERMINAL CLAMP FOR COIL-WINDING MACHINES.

1,270,077.

Specification of Letters Patent. Patented June 18, 1918.

Application filed March 11, 1918. Serial No. 221,872.

To all whom it may concern:

Be it known that I, AUGUST A. WALL, a citizen of the United States, and a resident of the city of New York, borough of Brooklyn, in the county of Kings and State of New York, have invented a new and Improved Terminal Clamp for Coil-Winding Machines, of which the following is a full, clear, and exact description.

10 The invention relates to armature coil winding machines, and its object is to provide an improved device to permit the attendant of the machine to quickly, with one single movement, clamp the wires in position without injury to the wires and without possibility of any one wire slipping during the operation of forming the coil; also to permit an instant release of the wires. By the use of the device the leads of coil are left perfectly straight and even so that the subsequent work of putting on tubing and of turning the leads is made much easier.

15

In order to produce the desired result, use is made of a clamping block provided with 20 an abutment for the rear side of a wire to rest against, and a clamping lever fulcrumed on the said block and provided on its fulcrum with an eccentric cam disposed opposite the said abutment, the lever being provided with a holding down plate projecting 25 beyond the cam and adapted to pass over the top of the wires to hold the same down on the block.

A practical embodiment of the invention is represented in the accompanying drawings forming a part of this specification in which similar characters of reference indicate corresponding parts in all the views.

Figure 1 is a plan view of the clamping 0 device as applied;

Fig. 2 is a front elevation of the same;

Fig. 3 is a rear elevation of the same;

Fig. 4 is an end elevation of the same;

Fig. 5 is an inverted plan view of the 5 clamping lever with the eccentric cam shown in section; and

Fig. 6 is a perspective view of the abutment.

The clamping block 10 of the clamping device is provided with a flange 11 fastened by bolts 12 to a part 13 of an armature coil winding machine of usual construction. To the rear of the block 10 is secured an abutment 15 by screws 16, and this abutment 15 has its upper portion 17 extending above the

top of the block 10. The upper portion 17 is concave and roughened, as plainly indicated in Fig. 6, and in this concave roughened portion fits the rear side of the rear-most wire of the series of wires 18 to be 60 clamped in place one alongside the other, as plainly indicated in the drawings.

The block 10 is provided with a vertically disposed pivot 20 on which is mounted to swing a clamping lever 21 provided at its 65 fulcrum end with an eccentric cam 22 adapted to engage the outer side of the front wire 18 so as to force the wires one against the other and the rearmost wire against the portion 17 of the abutment 15. The face of the 70 eccentric cam 22 is made concave so as to snugly fit the outer side of the front wire 18. The fulcrum end of the clamping lever 21 is further provided with an integral holding down plate 25 projecting beyond the face 75 of the eccentric cam 22, and this holding down plate 25 is adapted to overlie the wires 18 so as to hold the same firmly down against the back of the block 10. The forward side 26 of the holding down plate 25 is beveled 80 to gradually press the wires downward onto the block when swinging the lever 21 from open into closed position. It is understood that when the clamping lever 21 is in open position, as indicated in dotted lines in Fig. 85 1, then the wire 18 can be readily placed in position on top of the block 10 and then the clamping lever 21 is swung into closed position so that the cam 22 gradually presses the wires 18 transversely one against the 90 other and the rearmost into the concave top portion 17 of the abutment 15. During this closing movement of the lever 21 the beveled side 26 of the holding down plate 25 gradually engages the wires 18 and presses the 95 same downward against the top of the block 10 thus holding the wires firmly clamped in position on the block and with the wires arranged one alongside the other. The holding down plate 25 is sufficiently long to project onto or overlie the top of the abutment 15 when the lever 21 is in closed position so that there is no possibility of the wires 18 moving out of place during the time the clamping lever is in closed position. It will 100 be noticed that the clamping lever can be readily swung into open position to permit of receiving the wires 18 whenever it is desired to do so.

Having thus described my invention, I 110

claim as new and desire to secure by Letters Patent:

1. A wire clamp for coil winding machines, comprising a block adapted to be secured to the machine and provided with an abutment, and a clamping lever pivoted on the said block and having an eccentric cam disposed opposite the said abutment to clamp the wire or wires in place between the abutment and the eccentric cam, the clamping lever having a holding down plate projecting beyond the cam and adapted to overlie the clamped portions of the wire or wires to hold the same against the block.
2. A wire clamp for coil winding machines, comprising a block adapted to be secured to the machine and provided with an abutment, and a clamping lever pivoted on the said block and having an eccentric cam disposed opposite the said abutment to clamp the wire or wires in place between the abutment and the eccentric cam, the clamping

lever having a holding down plate projecting beyond the cam and adapted to overlie the clamped portions of the wire or wires to hold the same against the block, the said plate having a beveled side.

3. A wire clamp for coil winding machines, comprising a block provided with means whereby it may be secured to a support and with an abutment having a concave roughened face for the reception of the rear side of a wire, and a clamping lever pivoted on the said block and provided with an eccentric cam having a concave face and disposed opposite the said abutment to clamp the wire or wires in place between the abutment and the eccentric cam, the clamping lever having a holding down plate projecting beyond the cam and adapted to overlie the clamped portions of the wire or wires to hold the same against the block.

AUGUST A. WALL.
